UNITED STATES PATENT OFFICE

119,284

DESIGN FOR A COMBINED COMPACT, MEMO PAD, AND PENCIL

Arthur A. Rosenberg, Woodmere, N. Y.

Application January 17, 1940, Serial No. 89,518

Term of patent 3½ years

To all whom it may concern:

Be it known that I, Arthur A. Rosenberg, a citizen of the United States of America, residing at Woodmere, county of Nassau, and State of New York, have invented a new, original, and ornamental Design for a Combined Compact, Memo Pad, and Pencil, of which the following is a specification, reference being had to the accompanying drawing, forming part thereof.

Fig. 1 is a perspective view of a combined compact, memo pad and pencil showing my new design.

Fig. 2 is a perspective view in open position.

Fig. 3 is a perspective view showing the opposite side of Fig. 2 and showing the memo pad compartment in open position.

I claim:

The ornamental design for a combined compact, memo pad and pencil, substantially as shown.

ARTHUR A. ROSENBERG.
